Morris Paull, Rochester, N.Y., assignor to Atron Corp.,
Rochester, N.Y., a corporation of New York

Filed Oct. 13, 1964, Ser. No. 82,163

Term of patent 14 years

(Cl. D61—1)

FIG. 2

FIG. 3

FIG. 1 is a perspective view of a combined projector and sound reproducer, showing my new design;

FIG. 2 is a rear elevation thereof; and

FIG. 3 is an end elevation thereof.

This application is a continuation-in-part of my application Serial Number D-74,193, filed March 29, 1963, and now abandoned.

I claim:

The ornamental design for a combined projector and sound reproducer, substantially as shown and described.
